VAULT

Josiah H. Roberts, Wharton, N. J.

Application July 1, 1935, Serial No. 29,326

1 Claim. (Cl. 72—7)

The invention relates to a vault and more especially to a precast reinforced burial vault.

The primary object of the invention is the provision of a vault of this character, wherein the body and the cover thereof are made from precast cementitious or concrete substances having embedded therein reinforcements to give strength and rigidity so as to increase the life of the vault, and such cover is sealed in place upon the body to exclude water and moisture from without the vault.

Another object of the invention is the provision of a vault of this character, wherein the interior of the body has formed therein risers constituting supports for a coffin when placed within the body and also seat shelf-like parts, these being perforated so that drainage is permitted beneath the coffin in event that water gains entrance to the interior of the vault, the coffin being supported elevated from these parts so that circulation may be had entirely about said coffin when within the vault.

A further object of the invention is the provision of a vault of this character, which is simple in construction, thoroughly reliable and efficient in service, strong, durable, and inexpensive to manufacture.

With these and other objects in view, the invention consists in the features of construction, combination and arrangement of parts as will be hereinafter more fully described, illustrated in the accompanying drawing, which discloses the preferred embodiment of the invention and pointed out in the claim hereunto appended.

35 In the accompanying drawing:

Figure 1 is a vertical longitudinal sectional view through a vault constructed in accordance with the invention.

Figure 2 is a sectional view on the line 2—2 of Figure 1.

Figure 3 is a sectional view on the line 3—3 of Figure 1.

Figure 4 is a plan view partly in section of one of the shelf-like parts arranged interiorly of the vault.

Similar reference characters indicate corresponding parts throughout the several views in the drawing.

Referring to the drawing in detail, the vault, preferably made of cast concrete or cementitious material, comprises a body A and a cover B, respectively. This body A includes a bottom 10, side walls 11 and end walls 12 while the cover B is in the form of a slab 13, it having in the under face 55 thereof close to the edges of the same a continu-

ous groove or channel 14 to accommodate the upper edges of the side and end walls 11 and 12 of the body A and these edges are held sealed within the channels or grooves through the medium of a sealing medium 15 so as to exclude moisture, air and water from without the vault to the interior thereof.

The body A and the cover B have embedded therein crossed reinforcements 16 to give strength and rigidity thereto.

Cast with the bottom and end walls of the body A are inwardly extending thickened portions or risers 17 and cast with the sides and bottom 10 of the body are spaced intermediate risers 18. The risers 17 have their upper edges grooved as at 17' and the intermediate risers 18 are centrally formed with longitudinally extending ribs 18'. The grooves 17' and the ribs 18' have seated therebetween shelf-like sections or parts 20 which are made from cast concrete having the crossed 20 reinforcements 21. The slabs or sections 20 are of a lesser thickness than that of the depth of the grooves 17' or the height of the ribs 18', so that a casket will rest directly on the risers 17 and the ribs 18'. 25

The risers 18 next to the bottom 10 of the body A are formed with upwardly arched openings 22 while the shelf-like sections or parts 20 have the copper lined apertures 23 so that water and moisture can pass to the bottom of the body A below a 30 coffin when resting upon the risers 17 and 18. In this position the coffin will be slightly elevated from the shelf-like sections or parts 20 so that water and moisture may descend through the apertures 23 beneath the said shelf-like sections or 35 parts while the openings 22 in the risers 18 establish communication with the spaces between the risers.

The body A interiorly close to the upper edges of the side walls 11 and the end walls 12 has provided the sockets 24 for accommodating a lowering device (not shown) to permit the convenient lowering of the vault in place within a grave or at the point of deposit therefor, the lowering device being engaged with the body A prior 45 to the application of the cover to said body.

The cover carries a pair of hanger eyes 25 for the attachment of the lowering device therewith so that said cover B can be lowered into position onto the body A for the sealing of the latter after 50 the placing of a coffin therein.

The body A and the cover B with the reinforcements 16 embedded therein will have maximum strength and durability and when the cover B is sealed upon the body A the vault is rendered liq- 55

uid and air tight while within is assured proper drainage of moisture and water and removed from the point of rest of the coffin within the vault.

What is claimed is:

- 5 A reinforced concrete vault comprising a substantially rectangular body having its bottom and end walls thickened to provide risers which project a distance from the bottom wall and which risers have their upper and outer corners grooved
10 longitudinally, and intermediate risers cast between the bottom and side walls of the body and having central upstanding longitudinal ribs of a height equaling the depth of the grooves in end risers, said intermediate risers having arched

openings at their juncture with the bottom wall of the body to provide air passages and concrete slabs having series of spaced and reinforced openings therethrough designed to rest in the grooves and between the ribs of the respective end and intermediate risers and which slabs are of a thickness less than the depth of the grooves and the height of the ribs of the respective risers to allow a casket to rest directly on the end risers and the ribs of the intermediate risers and to permit air 10 circulating between the bottom of the body and the bottom of the casket. 5
